UNITED STATES PATENT OFFICE.

OSWALD REICHE, OF NORFOLK, NEBRASKA.

DIRECTION SIGNAL FOR AUTOMOBILES.

Application filed November 8, 1924. Serial No. 748,723.

This invention relates to direction signals for automobiles, and more particularly to a manually controlled direction signal having illuminating means actuated when the signal is in any of a number of given positions.

An important object of the invention is to provide a device of this character which may be cheaply and readily produced, which 10 is readily assembled, and in which the construction is such that there is little likelihood of the device becoming inoperative in use.

A still further object of the invention is 15 to provide a device of this character which may be employed with either closed or open vehicles.

These and other objects I attain by the 20 construction shown in the accompanying drawings, wherein for the purpose of illustration is shown a preferred embodiment of my invention and wherein:—

Figure 1 is a side elevation of a signal 25 constructed in accordance with my invention;

Figure 2 is a vertical sectional view thereof;

Figure 3 is a section on the line 3—3 of 30 Figure 2;

Figure 3^a is a section on the line 3^a—3^a of Figure 2.

Figure 4 is a perspective of the clamp 35 employed for holding this signal in position upon the vehicle.

Referring now more particularly to the drawings, the numeral 10 indicates a cylindrical metallic drum provided interiorly with a lamp socket 11, one terminal of which is grounded to the casing. The second terminal of this socket is connected in series 40 with a plurality of contacts 12 extending through and insulated from the drum wall at points spaced circumferentially thereabout in a common plane at right angles to the axis of the drum. The contact ends of these contact members are formed to provide V-shaped lugs as shown. The casing is provided interiorly with circumferentially spaced, transversely extending spacer elements 13, the ends of which are provided 45 with resilient tongues 14 against which are engaged the peripheries of lenses 15 closing the ends of the drum. The lenses are maintained in engagement with the resilient 50 tongues 14 by means of collars 16 having bayonet slot engagement with the ends of

the drum, as at 17, and having intermediate their ends upon their inner faces outstanding flanges 18 engaging the outer surfaces of the lenses.

An outer drum 19 is provided of greater diameter than the drum 10 and forming the casing for the drum 10. This outer drum 19 is open-ended and has applied to the ends thereof retaining rims 20 having bayonet slot engagement with the outer drum, as at 21, and having at their inner edges inwardly projecting flanges 22 engaging against the outer faces of the flanges 18 of the collars 16 and slidably abutting with their outer faces the inner walls of these collars, so that the inner drum 10 is rotatably mounted within the outer drum but held against longitudinal movement therein. This outer drum is provided with a tubular extension 23 within which is arranged a spring-pressed latch 24 having in the face thereof next adjacent the inner drum a notch 25 receiving the contact members 12 as they come into alignment therewith. The outer end of this contact is electrically connected with one terminal of a source of current 26, the opposite terminal of which is grounded to the casing drum at the tubular extension thereof, as indicated at 27. Secured to the drum 10 and wound thereabout in opposite directions are a pair of flexible elements 28 and 29, the free ends of which are provided with means, as at 30, whereby they may be readily engaged with the hand. 50 These ends are trained out through the tubular extension 23, and it will be obvious that by pulling upon one of these flexible elements the drum will be rotated in one direction and by pulling upon the other thereof the drum will be rotated in the opposite direction.

Since the latch also forms a contact for supplying current to an illuminating element 31 disposed within the socket 11, it will be obvious that as each of these members comes into engagement with the latch the signal is illuminated and if left in engagement therewith will continue to be illuminated. The means for securing the contact with the latch member preferably consists in a pair of nuts 32 engaged with the end of this latch member and which by their engagement with a tube 33, through which the latch member operates, prevent the latch member intermediate the contacts 12 from coming into an electrical engagement with

the inner drum 10 and thus short-circuit the source of current 26. The lenses 15 have arranged thereon an indicator pointer 34 showing the position in which the signal 5 is arranged. The tube 33 is insulated from the casing as at 33^a.

It will be obvious that since the operation of this device takes place through the tubular extension, a device of this character may 10 be readily applied to a closed vehicle by simply forming through the wall of the vehicle an opening through which this tubular extension may be disposed. Interiorly of the vehicle, this tubular extension may be engaged 15 with a bracket plate, such as shown at 35, having an opening 36 through which the tubular extension may be disposed and a clamping screw 37 for holding this tubular extension in engaged position. The edges of 20 the plate are formed to provide flanges having spaced openings 38 for the reception of a securing element which may be engaged with the woodwork of the vehicle. In order that such a plate may be likewise employed 25 where it is desired to secure the device in position upon an open vehicle and upon the windshield frame thereof, the under surface of the plate is formed with a shallow concave notch 39 extending entirely across the 30 plate between two adjacent openings 38. These openings may be then employed for reception of the ends of the arms of a U-bolt 40 for clamping the plate in position upon the windshield frame.

35 It will be obvious that the construction hereinbefore set forth is capable of a certain range of change and modification without materially departing from the spirit of my invention, and I accordingly do not limit 40 myself to such specific structure except as hereinafter claimed.

I claim:

1. In a signal of the character described, an outer drum, an inner drum rotatable 45 within the outer drum, a socket for an illuminating element within the inner drum, a latch element carried by the outer drum and free from contact with and insulated from the inner drum, a plurality of coacting 50 latch elements carried by the inner drum and insulated from the inner drum and adapted to successively engage with the latch element of the outer drum, the latch elements of the inner drum being each connected with one 55 terminal of the socket of the inner drum, the second terminal of the socket of the inner drum being connected with the drum, means for rotating the inner drum and lenses having pointer indicia carried by the inner drum.

2. In a signal of the character described, an outer drum, an inner drum rotatable with 60 in the outer drum, a socket for an illuminating element within the inner drum, a latch element carried by the outer drum, a plural-

ity of coacting latch elements carried by the inner drum and adapted to successively engage with the latch element of the outer drum, the latch elements of the inner drum being each connected with one terminal of 70 the socket of the inner drum, the second terminal of the socket of the inner drum being connected with the drum, means for rotating the inner drum, lenses having pointer indicia carried by the inner drum, the latch 75 element of the outer drum having a stem, a casing through which the stem extends, a spring within the casing projecting the latch element toward the inner drum, and means at the outer end of the stem for attaching 80 thereto a lead wire and for limiting the movement of the outer drum carried latch element toward the inner drum.

3. In a signal of the character described, an outer drum, an inner drum rotatable 85 within the outer drum, a socket for an illuminating element within the inner drum, a latch element carried by the outer drum and free from contact with and insulated from the inner drum, a plurality of coacting latch 90 elements carried by the inner drum and insulated from the inner drum and adapted to successively engage with the latch element of the outer drum, the latch elements of the inner drum being each connected with one 95 terminal of the socket of the inner drum, the second terminal of the socket of the inner drum being connected with the drum, and means for rotating the inner drum, lenses having pointer indicia carried by the inner 100 drum, the latch element of the drum being spring-pressed and having a notch receiving the coacting latch element of the inner drum and to thereby yieldably maintain the inner drum in adjusted position.

4. In a signal for automobiles, an inner cylindrical drum having its ends closed by lenses, bearing pointer indicia, an illuminating element within the drum, means for retaining the lenses in position in the drum and including means providing upon the drum at opposite ends thereof outstanding longitudinally directed perimetric flanges, an outer drum of greater size than the inner drum, retaining rims engaged with opposite 110 ends of the outer drum and each having at their inner edges inwardly projecting flanges engaging against the inner faces of said perimetric flanges to thereby rotatably 115 support the inner drum within the outer drum.

5. In a signal for automobiles, an inner cylindrical drum having its ends closed by lenses, having pointer indicia, an illuminating element within the drum, means for retaining the lenses in position in the drum and including means providing upon the drum at opposite ends thereof outstanding longitudinally directed perimetric flanges, an outer drum of greater size than the inner 120 drum.

5 arum, retaining rims engaged with opposite ends of the outer drum and each having at their inner edges inwardly projecting flanges engaging against the inner faces of said perimetric flanges to thereby rotatably support the inner drum within the outer drum, the outer drum having a radial tubular extension, and means operable through 10 said tubular extension for rotating the inner drum.

6. In a signal for automobiles, an inner cylindrical drum having its ends closed by lenses, bearing pointer indicia an illuminating element within the drum, means for retaining the lenses in position in the drum and including means providing upon the drum at opposite ends thereof outstanding longitudinally directed perimetric flanges, an outer drum of greater size than the inner drum, retaining rims engaged with opposite ends of the outer drum and each having at their inner edges inwardly projecting flanges engaging against the inner faces of said perimetric flanges to thereby rotatably support the inner drum within the outer drum, the outer drum having a radial tubular extension, and means operable through said tubular extension for rotating the inner drum comprising flexible elements 25 wound about the drum having their ends extended through the tubular extension of the outer drum.

7. A signal for automobiles including an inner and an outer drum, the inner drum comprising a cylinder, lenses having pointer indicia engaged with opposite ends of the cylinder, means within the cylinder for limiting the movement of the lenses into the cylinder, collars engaged with the cylinder and having inwardly extending flanges engaging the outer faces of the lenses, said flanges being arranged intermediate the ends of the collars, the outer drum comprising a cylinder, retaining rims engaged with opposite ends of the cylinder and provided at their inner edges with inwardly projecting flanges engaging the outer faces of the lens retaining flanges of the collars and slidably abutting with their outer faces the inner walls 50 of said collars to thereby rotatably support the inner drum within the outer drum and maintain the inner drum against longitudinal movement with relation to the outer drum.

8. A signal for automobiles including an

inner and an outer drum, the inner drum comprising a cylinder, lenses having pointer indicia engaged with opposite ends of the cylinder, means within the cylinder for limiting the movement of the lenses into the cylinder, collars engaged with the cylinder and having inwardly extending flanges engaging the outer faces of the lenses, said flanges being arranged intermediate the ends of the collars, the outer drum comprising a cylinder, retaining rims engaged with opposite ends of the cylinder and provided at their inner edges with inwardly projecting flanges engaging the outer faces of the lens retaining flanges of the collars and slidably abutting with their outer faces the inner walls 60 of said collars to thereby rotatably support the inner drum within the outer drum and maintain the inner drum against longitudinal movement with relation to the outer drum, 70 means for rotating the inner drum, and means for maintaining the inner drum in adjusted position.

9. A signal for automobiles including an inner and an outer drum, the inner drum comprising a cylinder, lenses having pointer indicia engaged with opposite ends of the cylinder, means within the cylinder for limiting the movement of the lenses into the cylinder, collars engaged with the cylinder and having inwardly extending flanges engaging the outer faces of the lenses, said flanges being arranged intermediate the ends of the collars, the outer drum comprising a cylinder, retaining rims engaged with opposite ends of the cylinder and provided at their inner edges with inwardly projecting flanges engaging the outer faces of the lens retaining flanges of the collars and slidably abutting with their outer faces the inner walls 80 of said collars to thereby rotatably support the inner drum within the outer drum and maintain the inner drum against longitudinal movement with relation to the outer drum, means for rotating the inner drum, 85 and means for maintaining the inner drum in adjusted position.

In testimony whereof I hereunto affix my signature.

OSWALD REICHE.
